CLAIM

The ornamental design for a cosmetic container with color chip, as shown and described.

DESCRIPTION

FIG. 1 is a front perspective view of the container in the closed position showing the color chip on the top surface; FIG. 2 is a front view thereof;

FIG. 3 is a top plan view thereof showing the color chip; and, FIG. 4 is a bottom plan view thereof.

The rear view of the design is identical to the front view shown in FIG. 2.
